UNITED STATES PATENT OFFICE.

GRANVILLE J. MILLER, OF FORT DEFIANCE, VIRGINIA.

TELEPHONE-DESK AND BOOK-SUPPORT.

1,046,100.

Specification of Letters Patent.

Patented Dec. 3, 1912.

Application filed May 15, 1912. Serial No. 697,578.

To all whom it may concern:

Be it known that I, GRANVILLE J. MILLER, a citizen of the United States, residing at Fort Defiance, in the county of Augusta and State of Virginia, have invented certain new and useful Improvements in Telephone-Desks and Book-Supports, of which the following is a specification, reference being had to the accompanying drawings.

10 This invention relates to an improved telephone desk and book holder, the object of the invention being to provide a device of this character adapted to be secured to the wall upon one side of the telephone to support a book or the like and is particularly valuable for use in stores, when taking orders over the telephone.

Another object of the invention is to provide a device of this character which will 20 securely hold the book in place, whereby a person can hold the receiver in one hand and at the same time can be writing in the book with the other hand.

Another object of the invention is to provide a device of this character which will 25 possess advantages in points of efficiency and durability, is inexpensive to manufacture and at the same time is simple in construction and operation.

30 With the above and other objects in view, the invention consists in the novel features of construction and the combination and arrangement of parts hereinafter more fully described, pointed out in the claim, and 35 shown in the accompanying drawings, in which,

Figure 1 is a perspective view of my improved telephone desk and book holder. Fig. 2 is an end elevation. Fig. 3 is a sectional view on the line 3—3 of Fig. 2.

40 Referring more particularly to the drawings, 1 indicates the substantially rectangular inclined body of the support which is formed of sheet metal or other suitable material and is provided at its intermediate portion with a substantially semicircular longitudinal groove 2. The upper edges of the groove are curved as shown at 3, so that when a book is placed upon the body 1 and

50 the back of the book arranged in the groove, the upper curved edges 3 will resiliently engage the back of the book to hold the same securely in place and prevent any movement thereof. Pivots secured to the upper corners of the body 1 are the resilient clips 4 55 which engage over the leaves of the book, when the same is open, so as to hold them securely in place when writing thereon.

5 The body plate 1 is secured to the wall and supported in an inclined position as shown 60 in Fig. 2 by means of the angular brackets 5 arranged at each end thereof. The lower edge of the body plate 1 is secured to the inwardly turned ends 6 of the horizontal portions of the brackets by means of the 65 rivets 7, and the upper edge of the body plate is secured to the inwardly turned ends 8 of the vertical portions of the brackets by means of the rivets 7'. The brackets 5 are secured to the wall by means of the screws 70 9 which pass through the openings 10 in the vertical portions of the brackets 5. It will be understood that the horizontal portions of the brackets 5 may be made any desired 75 length according to the inclination desired by the body plate 1.

While I have shown and described the above device adapted for use as a telephone desk or book holder, it will be understood that the same may be used for any desired 80 purpose, and it will be readily apparent that I have provided a simple, inexpensive and durable device of the above character which can be manufactured at an extremely low cost.

85 While I have shown and described the preferred form of my invention it will be obvious that various changes in the details of construction and in the proportions may be resorted to for successfully carrying my 90 invention into practice without sacrificing any of the novel features or departing from the scope thereof.

What I claim is:—

95 In a device of the character described, the combination of a metallic body plate having a substantially semicircular longitudinal groove formed in its intermediate portion,

the upper edges of said groove being bent inwardly to resiliently engage the back of a book, angular brackets arranged at each end of the body plate, said brackets having their ends bent inwardly and secured to the upper and lower edges of the body plate and means for securing the brackets to a wall or other stationary support.

In testimony whereof I hereunto affix my signature in the presence of two witnesses. 10

GRANVILLE J. MILLER.
